US0D1025742S

(12) **United States Design Patent** (10) **Patent No.:** **US D1,025,742 S**
(45) **Date of Patent:** **** May 7, 2024**

(54) **LOCK**

(71) Applicant: **Ningbo Eudemon Child Protective Equipment Co., Ltd.**, Ningbo Zhejiang (CN)

(72) Inventor: **Binhui Li**, Zhejiang (CN)

(73) Assignee: **Ningbo Eudemon Child Protective Equipment Co., Ltd.**, Ningbo (CN)

(**) Term: **15 Years**

(21) Appl. No.: **29/911,285**

(22) Filed: **Aug. 31, 2023**

Related U.S. Application Data

(62) Division of application No. 35/515,592, filed on Nov. 3, 2022 (U.S. filing date under 35 U.S.C. 384), and having an international filing date of Nov. 3, 2022.

(57) **CLAIM**

The ornamental design for a lock, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, left side perspective view of a lock, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded perspective view thereof.

1 Claim, 8 Drawing Sheets
